UNITED STATES PATENT OFFICE.

NATHANIEL E. ROSS, OF VERSAILLES, OHIO.

DITCHING-MACHINE.

SPECIFICATION forming part of Letters Patent No. 270,987, dated January 23, 1883.

Application filed September 15, 1882. (No model.)

To all whom it may concern:

Be it known that I, NATHANIEL E. ROSS, a citizen of the United States, residing at Versailles, in the county of Darke and State of Ohio, have invented a new and useful Ditching-Machine, of which the following is a specification, reference being had to the accompanying drawings.

Figure 1 is a plan view of my improved ditching-machine. Fig. 2 is a front view of the same. Fig. 3 is a longitudinal vertical sectional view, and Fig. 4 is a vertical transverse section.

Corresponding parts in the several figures are denoted by like letters of reference.

This invention relates to ditching-machines; and it consists in certain improvements in the construction of the same, which will be hereinafter fully described, and particularly pointed out in the claim.

In the drawings, A represents a rectangular frame, mounted upon the front and rear axles, B C, the former of which is swiveled under the front end of the frame upon the king-bolt D, while the latter revolves in suitable boxes, E, under the rear end of the frame. The front wheels, F, are loose and the rear wheels, G, fixed upon their respective axles.

Between the front beam of frame A and a transverse cross-beam, H, near the latter, is fitted a block, I, having bearings for a vertically-sliding frame, J, carrying a vertical rack-bar, K. Uprights L upon block I have bearings for a shaft, M, provided with a crank, N, and having a pinion, O, engaging the rack K. Shaft M also has a ratchet-wheel, P, engaging a pawl, Q. By this mechanism the frame J may be raised or lowered and retained at any desired elevation.

The sides of frame A have downward-projecting brackets or hangers R, supporting a transverse frame, S, which consists essentially of two side pieces connected by suitable braces. Said frame S is capable of sliding in the hangers or brackets R longitudinally in relation to frame A. The sides T of frame S extend from one end of the latter to near the ground, and at the upper and lower ends are journaled shafts U V, upon which runs an elevator-belt, W. The front side, T, of frame S has bear-

ings for a shaft, X, on which is journaled the upper end of an elevator-frame, Y, having at its lower end a shaft, Z, upon which shaft X the belt A', having suitable carrying-buckets, is mounted.

B' is a prismatic shaft, mounted in the cross-beam H and in a transverse beam, C', connecting the brackets R in such a manner that it may be slid for a short distance longitudinally in its bearings by means of a forked lever, D', engaging a groove, E', in said shaft. Shaft B' has at its rear end a pinion, F', receiving motion from a gear-wheel, G', fixed upon the rear axle of the machine, but capable of being thrown out of engagement by 65 sliding the shaft rearwardly. Mounted loosely upon the prismatic shaft, in such a manner as not to interfere with its sliding motion, is a gear-wheel, H', having teeth both upon its side and edge, engaging pinions I' J' upon the 70 shafts V and X, thus operating the elevator-belts W and A', respectively. A small suitably-constructed frame, K', confines the gear-wheel H' closely beside frame S.

To the lower end of the elevator-frame Y is 75 hinged the ditching-scoop L', which in turn is suitably connected to the lower end of the vertically-adjustable frame J.

The operation of my invention will be readily understood from the foregoing description, taken in connection with the drawings hereto annexed. By raising or lowering the frame J the ditching-scoop may be adjusted so as to dig a ditch of any desired depth, the elevator-frame Y being simultaneously adjusted so as to convey the dirt to the elevator W, by which it is deposited at the side of the machine. When the elevator Y is raised or lowered the frame S of elevator W slides longitudinally in the brackets R, so as to permit 90 the desired adjustment without interfering with the operation of the machine.

I claim and desire to secure by Letters Patent of the United States—

The combination of the frame A, the longitudinally-sliding transverse elevator-frame S, having operating-shaft V, provided with pinion I', the shaft X, having pinion J', longitudinal elevator-frame Y, having hinged ditching-scoop L', vertically-adjustable frame J, 100

suitably connected to said scoop, the longitudinally-sliding prismatic shaft B', having pinion F', capable of engaging a gear-wheel fixed upon the revolving rear axle of the machine, and a gear-wheel mounted loosely upon said prismatic shaft, and having teeth on its side and edge engaging the pinions I' J', all substantially as set forth.

In testimony that I claim the foregoing as my own I have hereto affixed my signature to in presence of two witnesses.

NATHANIEL EDWARD ROSS.
